UNITED STATES PATENT OFFICE.

WILLIAM E. SMALL, OF BROOKLYN, NEW YORK.

HEEL LIFT.

Application filed November 26, 1923. Serial No. 676,988.

To all whom it may concern:

Be it known that WILLIAM E. SMALL, citizen of the United States, residing at Brooklyn, in the county of Kings and State of New York, has invented certain new and useful Improvements in Heel Lifts, of which the following is a specification.

My invention relates to an article of manufacture, viz; lifts, for building heels for boots and shoes, the same to be used in a device especially provided therefor, to which more especial reference is made to my application for patent for a method and apparatus for building heels, disclosed in said application filed February 1st, 1921, serially numbered 441,538, and patented on March 25, 1924, #1,487,980, wherein layers of flat or tapered lifts of varying sizes are arranged in a series of successive layers, differing in diameter and thicknesses from each other for the particular purpose, each and every lift being placed over, and is held secure to the others by suitable adhesive material, and the complete assembled heel removably held in the assembling device until the mass of layers receive the first pressure.

One of the principal objects is to provide a heel lift made of a single piece of leather, or made up of scrap pieces, with interlocking means for holding the pieces together without other agencies, and provide the same with locking means therein or thereon, whereby the workman will not be hampered in assembling the various size lifts to build the desired heel. My lock forming the interlocking means hold the several pieces together as securely as if they were glued. Again, by having my locking means secured to each and every lift, prevents the slipping and sliding of the same in any direction, when assembled and ready for the first pressure to be applied, yet to have such assembled mass as readily removed from the device at the proper time.

My invention further consists in certain novel details of construction and combination and arrangements as will be herein-after described and pointed out particularly in the appended claims.

The invention as at present preferred will be more clearly understood by reference to the drawing which illustrates merely an example of means for putting my invention into practice, and wherein:—Fig. 1 is a view of a lift provided with a curved breast wherein is provided a suitably shaped

opening for the reception of a key; Fig. 2 is a like view showing the lift with a straight breast and provided thereon a projecting member of a lock, adapted to be held to a suitable device; Fig. 3 is a view of two pieces of scrap leather provided with a dove-tail lock for holding them together, the lift, after being thus assembled, is ready to be cut by the die as shown by dotted lines, illustrating another style of opening adapted to receive a suitable key; Fig. 4 is a like view showing a plurality of pieces secured together by modified forms of my locking means, the lift as it would appear when finished, is illustrated in dotted lines, showing the locking means applied to the breast of the lift, and Fig. 5 is a further modification showing rectangular openings, within which the pointed key grips and holds tight against the side walls of the openings.

Similar numerals of reference indicate like parts in the several figures of the drawing.

The building of heels for various styles of shoes, having as many varieties of heels as there are styles in shoes, becomes a serious question to the manufacturer, and in many cases where it becomes impracticable to build some styles of heels of layers, such for instance as the "French heel" as was customary, it having been found cheaper and much easier to cast them of metal or cut them from wood, thus avoiding the loss of labor and material. But in other styles of heels there is at present a great amount of waste of both time and labor, to say nothing of material, by reason of the systems now employed in manufacturing heels. To make a good perfect heel without nails, and other difficulties encountered especially when cupping the heel, it is necessary to provide a locking means on each lift that will hold the lift in its respective position, without movement while in the assembling device. With my improved lift, it affords every opportunity to apply the adhesive either by hand or automatically as each lift is placed in position, the whole mass after being assembled, is then ready for the pressure to be applied.

By providing the various lifts 6, be they the flat or the tapered or wedge variety, with a curved breast that fits a corresponding curve in the assembling device, (not shown) and providing the breast of the lift with a dove-tail slot 7, which is adapted to receive and house a suitable key to fit there-

in. It will be readily seen how each and every lift when placed one on top of the other with the key holding the mass secure to the assembling device, will prevent movement of any of the several layers, this notwithstanding that there may be one or more wedge shaped lifts therein.

Referring to Fig. 2, is shown a lift provided with a flat face or breast 8 and having a projecting part or key 9, that is adapted to fit into a corresponding opening in the breast plate (not shown) in this modification, as in the other designs, the various lifts are securely held in position by the key 9 holding the face of the lifts tightly against the breast plate, thus assisting materially in holding the lifts against movement.

Referring to Fig. 3 in which is shown the adaptability of my lock applied to hold pieces of scrap leather to form a lift, and at the same time using the same style of locking means to hold the whole assembled mass of lifts to the assembling device. In this figure is used the dove-tail projection 10 on one piece, while the other piece is provided with a corresponding opening 11 to receive the projection, when the pieces are placed together they fit so perfectly that there is not the slightest danger of their pulling apart. Again in Fig. 4 is shown the interlocking idea used when two or more pieces of scrap leather are used, the various styles of locks 12, 13 and 14 shown, being only illustrative of the many different forms that may be employed for locking the various lifts to the breast plate, which plate would be provided with the necessary opening or key to form the other member of the lock that would hold the mass of layers together. As before noted, by using my interlocking means on scrap pieces of leather, it obviates the necessity of pasting, stapling or otherwise securing the pieces together, and when once assembled together will remain in that position even when being applied to the mass of preceding lifts.

Referring now to Fig. 5 it will be seen that the lift is provided with two rectangular openings 15 which may be punched, stamped or otherwise placed therein, the key that is used in this style of opening may be of the T shaped variety, it having been found in the actual working of lifts of this style, that the outer edges of the T shaped key being

slightly sharpened, that the same would embed themselves in the side walls of the cutouts and hold the lifts secure to the breast plate. No matter what kind of a breast is on the lift, the lift and breast of the assembling device at all times acting in conjunction in holding the lifts secure thereto.

Thus it will be seen from what has been said about the several modifications, that the openings and keys are only examples of the various forms which the locking means may assume, be it, as has been noted, for either securing separate pieces of leather together to form lifts, or for securing said lifts in assembled built up mass. My cooperative lock insures the various styles of lifts being held permanently in their position while pressure is applied, and while those only that were thought the more important are illustrated, yet it is to be understood that various other forms of locks may be devised, but that all such other means are to come within the scope of the claims.

What I claim is:—

1. A heel lift provided with locking means adapted to engage with cooperative locking means associated with the heel assembling apparatus.
2. A heel lift provided with locking means on an edge thereof adapted to engage with cooperative means associated with the heel assembling apparatus whereby to hold the lift against movement.
3. A heel lift provided with locking means on the breast thereof adapted to engage with cooperative locking means on the heel assembling apparatus whereby to hold the lift against movement during the assembling operation.
4. A heel blank comprising a plurality of superposed lifts each of which is provided with locking means which engage with cooperative means associated with the assembling apparatus during the production of the blank, said locking means being subsequently removable during the finishing step.

5. A heel blank comprising a plurality of superposed lifts each of which is provided with locking means which engage with a common cooperative locking means associated with the assembling apparatus during the production of the blank.

In testimony whereof I affix my signature.
WILLIAM E. SMALL.
